AUTOMATIC GAS AND ELECTRICITY CONTROLLING DEVICE

Filed Aug. 8, 1927

UNITED STATES PATENT OFFICE

JACOB L. BLALACK, OF LOS ANGELES, CALIFORNIA

AUTOMATIC GAS AND ELECTRICITY CONTROLLING DEVICE

Application filed August 8, 1927. Serial No. 211,417.

This invention relates to automatic gas and electricity controlling devices.

The general object of this invention is to provide an improved device which will be actuated by earthquake tremors or fire to break an electric circuit and to shut off the gas in a building.

A specific object of my invention is to provide an improved circuit breaker wherein means is provided for breaking the electric circuit either by earthquake tremors or by excessive heat.

A further object of this invention is to provide a novel gas shut-off wherein means is provided for actuating the shut-off by either earthquake tremors or by excessive heat.

Another object of my invention is to provide a novel form of shut-off valve wherein means is provided for relieving the pressure beyond the valve when the valve is actuated to shut off the supply from the main feed pipe.

Other objects and advantages of this invention will be apparent from the following description taken in connection with the accompanying drawings wherein:

Fig. 1 is a sectional view through the housing containing my improved shut-off device.

Fig. 2 is a section taken on line 2-2 of Fig. 1 showing the device on a smaller scale.

Fig. 3 is an enlarged section of my improved shut-off valve taken on line 3-3 of Fig. 2, showing the valve in an open position.

Fig. 4 is a view similar to Fig. 3 showing the valve in a closed position, and

Fig. 5 is a diagrammatic showing of a preferred method of hook-up used to cause my improved controlling device to be actuated by a fire in a building with which it is associated.

Referring to the drawing by reference characters I have indicated my improved device generally at 10. The device 10 includes an electric circuit breaker indicated generally at 11 and a gas control device indicated generally at 12. The electric circuit breaker 11 and the gas control device 12 are preferably mounted within a common housing 14 as shown.

The electric circuit breaker 11 comprises a knife switch 15 which is shown as a two pole type and includes a base 16 having mounted thereon a pair of terminals 17 and 18, a pair of blades 19 and 20 pivotally connected to the terminals 17 and 18 as at 21 and connected together by an insulated bar 22, and another pair of terminals 23 and 24. A lead in negative wire 25 connects with the terminal 18 and a take-off negative wire 26 connects with the terminal 24 as shown in Fig. 2. A lead in positive wire 27 connects to a terminal 28 mounted on an insulated base 29 and from the terminal 28 the positive current is conducted through a fusible member or rod 30 to another terminal 31. A positive wire 32 connects the terminals 17 and 31 and a take-off positive wire 33 connects with the terminal 23.

For actuating the knife switch 15 to cause the circuit to be broken I provide a weighted member or ball 35 which is connected to the bar 22 of the switch by a cord or chain 36 as shown. The ball 35 is normally positioned upon a seat 37 of a horizontal arm 38 of a bell crank rocker arm 39. The rocker arm 39 is pivotally connected as at 40 to a bracket 41 which is secured to the housing 14 and may be insulated from the bracket as shown at 42 or the whole rocker arm may be made of an insulating material. The arm 38 of the rocker arm 39 is retained in a horizontal position by another arm 43 which extends upward from the pivot point 40 and is positioned against the fusible bar 30.

From the foregoing description it will be seen that when heavy earthquake tremors cause the weighted ball 35 to become unseated from the arm 38 it will fall to the dotted line position shown in Fig. 1 and through the medium of the chain 36 actuate the knife switch to the dotted line position thereby breaking the circuit from the terminals 17 and 18 to the terminals 23 and 24, whereupon the danger of a fire caused by an electrical short circuit in the building protected by my device will be eliminated.

The gas control device 12 includes a valve 45 having an operating member 46 thereon to which is loosely connected an actuating

arm 47 provided at its free end with a weight 48. For retaining the actuating arm in a raised position I provide a catch 49 pivotally connected as at 50 to a bracket 51 secured to the housing 14. The catch 49 includes a hooked arm 52 which engages a loop 53 on the weight 48 of the arm 47 and normally supports the weight and arm to retain the valve in an open position.

10 For rocking the arm 52 to disengage it from the loop 53 the catch 49 is provided with an arm 54 which is connected to the insulated bar 22 of the knife switch 15 by a cord or chain 55 as shown in the drawings. 15 Thus it will be seen that when the ball 35 is unseated by either fire or shock as previously described the movement of the bar 22 of the knife switch will rock the lever 54 and the arm 52 to disengage the arm 52 from the loop 20 53 of the weight 48, whereupon the weight 48 will cause the arm 47 to move downward to the dotted line position, thereby moving the valve 45 to shut off the flow of gas into the building.

25 The loose connection of the arm 47 with the valve operating member 46 allows the arm 47 to gain momentum before it begins to actuate the valve so that if the parts become stiff in operation the energy of the descending weight will jar the parts and cause actuation.

30 In the accompanying drawing I have provided a guide 56 which prevents the arm 47 from swaying sideways when descending and 35 on the guide I have provided a stop 57 to limit the downward movement of the arm 47.

Various forms of switches and valves may be employed in connection with my device. In the accompanying drawing I have shown 40 the valve 45 as of novel construction wherein means is provided for relieving the pressure beyond the valve when the valve is actuated to shut off the flow from the main feed pipe. My improved valve 45 comprises a housing 60 45 provided with an inlet 61, an outlet 62, a by-pass outlet 63 and a rotatable core 64. The rotatable core 64 is provided with a feed passage 65 and by a by-pass passage 66. As shown in Fig. 3 when the actuating arm 47 50 is in the full line position shown in Fig. 1 the feed passage 65 forms a communicating passageway from the inlet 61 to the outlet 62 and the ends of the by-pass passage 66 does not communicate with either the inlet, outlet 55 or by-pass outlet.

As shown in Fig. 4 when the actuating arm 47 is in the dotted line position shown in Fig. 1 the by-pass passage 66 forms a communicating passageway from the outlet 62 to the by-pass outlet 63 and the ends of the feed passage 65 are closed by portions of the housing 60 and do not communicate with either the inlet 61 or the outlet 62. When the core 64 is in this position the gas beyond the control 60 valve may pass from the outlet 62 through the

passage 66 and out through the by-pass outlet 63, thus allowing the gas in the building to escape and eliminate the danger of an explosion or the firing of the gas.

With this construction if a gas burner is 70 in use at the time the valve 45 is operated the gas in the pipes within the building will be turned into the escape pipe 63 instantly relieving the pressure so that the flame at the burner will be immediately extinguished. 75 This would prevent any possibility of fire starting due to any combustible material coming into contact with the flame due to an earthquake shock.

In Fig. 5 I have shown diagrammatically 80 a preferred method of wiring my device so that a fire in a building will cause actuation of the device. In this view I have indicated a building generally at 70 and have shown the building as divided into a plurality of rooms each provided with a plurality of electric lights 71 which are supplied with current from the service wires 26 and 33. In each of the rooms of the building 70 and connected to the wires 26 and 33 I have shown at 72 85 my improved circuit controlling device which is fully described and shown in detail in my co-pending application Serial No. 206,401, filed July 18, 1927.

These devices 72 are so constructed that a 90 fire in the near vicinity thereof will cause a short circuit between the positive wire and the negative wire. When the devices 72 form a short circuit, the heat generated will fuse the rod 30, releasing the rocker arm 39, and causing the weight 35 to fall, whereupon the device 10 will be operated as previously described. It will be understood that the devices indicated at 72 may be any desired character although I prefer to use my invention 105 as above mentioned.

From the foregoing description it will be apparent that I have provided a novel form of combined electric circuit breaker and gas shut-off device which is either actuated by 110 earthquake tremors or by fire and one which is positive and efficient in operation.

Having described my invention, I claim:

1. In a device of the class described, a 115 knife switch, a weighted member connected to said switch, a seat for said member, said member being adapted to be unseated by earthquake tremors to actuate said switch to break the circuit therethrough, a valve, a second weighted member connected to said valve, a catch normally supporting said second member, and means whereby said catch is released by said first mentioned weighted member when unseated to release said second weighted member and actuate said shut-off valve.

2. In combination with distributing means for two media of different characteristics, a solid conductor for one of said media and a hollow conductor for the other of said media, means to control the passage of each of said 130

media through their respective conductors and a common means for actuating each of said control means to stop the passage of each of said media through their respective conductors, and means to operate said common means by action of earthquake tremors or fire.

3. In combination with gas and electricity distributing lines, a solid conductor for electricity and a hollow conductor for gas, means to control the passage of the electricity and gas through their respective conductors, a common means for actuating each of said control means to stop the passage of each of said media through their respective conductors, 10 said common means comprising a member mounted to be moved by seismic disturbances.

4. In a device of the class described, a housing, a knife switch mounted in and insulated from said housing, a pivoted member mounted in and insulated from said housing, said member including two arms, a fusible member for retaining said arms in set position, a bracket for supporting each end of said fusible member, said brackets being insulated 20 from said housing, a wire attached to one of said brackets, another wire connecting the other of said brackets to one side of said switch, a seat on one of said arms, a weight connected to said switch and normally positioned on 25 said pivoted member, said weight adapted to be unseated by earthquake tremors or by fire causing said fusible rod to melt, said weight when unseated being adapted to actuate said switch to break the circuit therethrough.

5. In a device of the class described, a housing, a pivoted rocker member mounted in said housing, said rocker member including two arms, a fusible member for holding said rocker member in set position, a seat on one 30 of said arms, a weight connected to said switch and normally positioned on said seat, said weight adapted to be released from said seat by earthquake tremors or by melting of said fusible rod, said weight when unseated being adapted to actuate said switch to break the circuit therethrough, a pipe valve and means operated by said weight for operating said pipe valve.

6. In a device of the class described, a housing, a switch mounted in and insulated from said housing, a pivoted rocker arm mounted in and insulated from said housing, said rocker arm including a substantially horizontal arm and a substantially vertical arm, a fusible bar for retaining said vertical arm in position, a bracket adjacent each end of said bar and supporting said bar, said brackets being insulated from said housing, a wire attached to one of said brackets, another wire connecting the other of said brackets to one side of said switch, a seat on one arm of said rocker arm, a weight connected to said switch and normally positioned on said rocker arm seat, said weight being adapted to be unseated by earthquake tremors or by fire causing melting of

said fusible rod to actuate said switch to break the circuit therethrough, a shut-off valve, said shut-off valve including an inlet, an outlet, a by-pass outlet and a core, a passage in said core adapted in one position of 70 said core to form a passageway from said inlet to said outlet, another passage in said core adapted when said core is in another position to form a passageway from said outlet to said by-pass outlet, said first passage 75 being adapted when said second passage is in full communication with said outlet and said by-pass outlet to be completely out of communication with said inlet and said outlet, and said second passage being adapted when said first passage is in full communication with said inlet and said outlet to be completely 80 out of communication with said outlet and said by-pass outlet and means operated by said weight when released for actuating said 85 cut-off valve.

7. In a device of the class described, a switch, a weight connected to said switch, a movable seat for said weight, a fusible member for holding said seat in an operative position, means to fuse said fusible member to release said seat to unseat said weight and break the circuit through said switch, said means including a device connected to a positive and to a negative wire of an electric 90 service system and including means whereby excessive heat in the vicinity of said device will cause said negative and said positive wires to be connected to form a short in said electrical system, the current in one of said 100 wires of said electrical system passing through said fusible member whereupon said member will be fused when a short circuit is formed in said electrical system.

In testimony whereof, I hereunto affix my 105 signature.

JACOB L. BLALACK.
